(57) **CLAIM**

The ornamental design for a tie plate for railroad, as shown and described.

DESCRIPTION

FIG. 1 is a perspective view of a tie plate for railroad;

FIG. 2 is another perspective view thereof;

FIG. 3 is a front elevation view thereof;

FIG. 4 is a rear elevation view thereof;

FIG. 5 is a left elevation view thereof; and

FIG. 6 is a right elevation view thereof.

FIG. 7 is top plan view thereof;

FIG. 8 is a bottom plan view thereof; and,

FIG. 9 is a cross-sectional view thereof, along cross-section line 9-9 of FIG. 7.

In FIGS. 1, 2 and 5-8, the broken lines depicts portions of the tie plate for railroad that form no part of the claimed design.

1 Claim, 9 Drawing Sheets
